ORBITAL LATHE

William F. Groene, Cincinnati, Ohio, assignor
to The R. K. Le Blond Machine Tool Com-
pany, Cincinnati, Ohio, a Corporation of
Delaware

Application November 18, 1929
Serial No. 407,814

9 Claims. (Cl. 82—9)

My invention relates to machine tools such as lathes, and more particularly to the performance of machining and cutting operations performed on a piece of work which is moving during the 5 operations thereon in an orbital path. In the structure shown my invention is applied to a crank shaft lathe in which crank pins are cut while the crank shaft is being rotated upon its bearings.

10 In an application for patent Serial No. 246,314, filed Jan. 12, 1928 by myself and Harold F. Siekmann, there is shown and described a crank shaft lathe for a similar purpose to the one illustrated herein for that construction, there were 15 frames which moved in eccentric paths and there were tools in the several frames for operating on two sides of a crank pin at once. The tools were provided with feeding devices, one for each frame, the particular mechanisms including fluid 20 pressure cylinders and rack and pinion mechanism mounted on each frame and connected to a master device.

In my present improvement I employ frames mounted and moved in eccentric paths, but provide 25 for the tool feed by bodily moving one of the sets of eccentrics which impart the work following movement to the entire group of frames thereby feeding the frames that carry the tools as a group, to and from the work.

30 Certain features illustrated in this application and some parts of the machine which have not been illustrated but are referred to are found in the Groene and Siekmann application above referred to in my application Ser. No. 283,712 35 filed June 7, 1928 for Steady rests; Ser. No. 297,881 filed Aug. 6, 1928 for Chucking devices; and Ser. No. 159,448 filed Jan. 6, 1927 for Air chucks.

In my present machine there is a flexibility to 40 the working structure where called for and a high degree to resistance to distorting forces which interfere with accuracy of workmanship, which features are part of the objects of the invention, as will be developed.

45 In the drawings:

Fig. 1 is a central transverse section on line A of Fig. 3.

Fig. 2 is a similar view on the same line but showing the parts in a fully retracted position.

Figure 3 is a view of the rear of the machine, the right hand end not being completed as to frame and gearing.

The base of the machine is shown at 1 and the 55 side housings, 2, are bolted thereto, these side

housings being tied together at their tops by tie bar 3 in the front, and by tie bar 4, in the rear.

A power shaft 5 extends across the lower part of the bed from side to side and beyond. On each end, outside the bed is mounted pinion gears 6, and as shown in Fig. 3, to the left the shaft 5 extends beyond the pinion 6, thus providing for a power application, as a motor, to drive the machine.

The side frames 2 are provided with bifurcated 65 or pocketed portions 7, as shown in Fig. 3, formed by integral webs in the housings of the frame, these web portions carrying bearings 8, one on each side housing. Journaled in the bearings are pins 9 having journal extensions 10. 70 Pivotally mounted on the pins 9 are arms 11a of a feed frame 11 which feed frame carries at its upper forward ends, bearings 12.

The base 1, at each side towards the rear, has a bearing 13 formed in it and mounted in these 75 bearings is a master crankshaft 14, this shaft having ends extending beyond the bearing. The eccentrics 14a on this shaft match the path of the pins of a crank shaft to be turned.

A second master crankshaft 15 is mounted in 80 the bearings 12 of the feed frame 11, and has extend ends similar to master crankshaft 14. This shaft also has eccentrics which match the movement of the pins of the crankshaft that constitutes the work.

85 Mounted in the side housings 2 at their forward part are a pair of crankshaft chucks 16, these chucks being similar to those shown in my heretofore mentioned pending applications; the spindles of these chucks provide for the mounting of 90 driving means.

Mounted on the master shaft 14 extensions at each end, are driving gears 16a shown in Figs. 1 and 2 by dotted pitch lines and in full lines in Fig. 3, these gears 16a meshing with the pinions 95 6 on the power shaft 5. The master shaft 15, has mounted on its extensions, driving gears 17 and the crankshaft chucks also have mounted on their spindles the driving gears 18.

The extension journals 10 of the pins 9 have 100 mounted on them idler gears 19. The idler gears mesh with gears 16, 17 and 18 of the master crankshafts and the chucks and thus form a complete drive at each end for the master shafts and the chucks from the source of power. As will be noted 105 the center of movement of the frame 11 is co-axial with that of the idlers 19, so that the gears 17 move in a planetary path about the idlers when the frame is moved.

A series of spacer frames 20 are mounted on 110

the bed by bolts 21a, these spacer frames being seated at their tops in notches 21 in the tie bars 3 and 4, the notches being wider than the frames 20 so that by means of adjusting screws 22, the frames 20 can be shifted sidewise slightly into perfect alinement with contiguous parts.

The spacer frames 20 also carry, at their front edge, extensions preferably serving as steady rests for the line bearings of a crankshaft where such rests are necessary.

At a point near the side housings are located thrust frames 23, these frames being similar to spacer frames 20 except that they need carry no extensions for steady rest purposes, their purpose being to offer resistance to thrusts from operating parts mounted between them and the spacer frames.

The thrust frames have, on their side toward the center of the lathe at their front and rear edges, fastened hardened steel rub plates 24.

The spacer frames 20 and also the tool frames to be described have on the front and rear edges of both their sides hardened steel rub plates 25, these plates providing a long wearing, friction reducing, bearing surface for the tool frames, spacer frames and thrust plates 23.

In the spaces left between the thrust and the spacer frames are mounted the tool carrying frames 26, these frames at their lower part have bearings 27, which are mounted on the eccentrics of the lower master crankshaft 14. On the eccentrics of the upper master crankshaft are mounted strap arms 27a having at their outer ends pin bearings 28. Pins 29 in these bearings serve to mount bifurcated arms 30, said arms having on one side the half bearings 31. In the upper front edges of the feeding frames 26 are located the half bearings 32.

The extensions of the bifurcated arms 30 are drilled for bolts 33, as are the upper front edges of the feeding frames 26, these bolt holes being each side of the half bearings in the two members. The pins 34, which are located in the two half bearings, 31 and 32, completes the tool frame assemblies and provide a slightly self-adjusting connection for the feeding frames to the two master shafts when one of the shafts is moved to the rear as will be explained later.

When one or the other of the bolts 33 is tightened or loosened, a fine size adjustment of the tool is obtained, and thereafter being permanently locked in position by the two bolts 33. When the feeding frame is in the position of turning the pin of a crankshaft, the eccentric driving of the tool frames is the same as if the strap arms 27a were bolted to, or a rigid part of, the feeding frame structures.

The particular machine illustrated is designed for an eight cylinder engine crankshaft and therefore requires three steady rests for the line bearings. These steady rests are the same as shown in my application now pending, as noted in an earlier part of this specification and consists of a hinged top clamping member 34a, a hinged pressure member 35, a wedge member 36 and a fluid pressure cylinder 37 to actuate the wedge. When the clamp is closed and valve 38 is operated and thus admitting pressure to the cylinder, the wedge member 36 is moved downward, rocking the pressure member 35 against the clamp thus holding it closed until the turning of the crankshaft is finished, whereupon the valve is again operated and the clamp released thus permitting it to be opened and the shaft removed.

As in the Groene and Siekmann application, the arrangement of the eccentric shafts is such as to leave the front of the machine free for insertion or withdrawal of the work.

A recess 39 is located in base of the machine at its center and extending from the rear almost to the front. Mounted in this recess is a fluid pressure cylinder 40, having a piston 41 and piston rod 42, this rod having an extending portion with the upper half cut away for part of its length and having a rack piece 43 fastened to the cutaway portion. The extended portion of the rod rides in a bearing 44 formed as part of a bracket 45, this bracket having its upper part formed as a pair of bearings 46. Mounted on a shaft 47 in this bearing is a toothed quadrant 48, this toothed quadrant having a portion extended to form an ear for a bearing 49. Mounted on a pin in bearing 49, is a bifurcated adjustable link 50, this link terminating in a bearing at its upper end.

At the center of the lower rear edge of feed frame 11, is formed a pair of ears or lugs 51 having bearings for a pin or shaft, 52. The upper bearing end of link 50 is placed between the ears 51 and pin 52 inserted thus completing an operative organization for rocking the feed frame and with it the upper master crankshaft and tool feeding frames. When the frames are thus moved the tools themselves move through part of the arc of a circle to and away from the work.

Provision is made for fluid connection to the cylinder 40 by conduits 53 in the bracket 45, these conduits leading the fluid to opposite ends of the cylinder and controlled by the usual type valves for admission and exhaust.

With the piston 41 and its parts as shown in Fig. 1 (the pin turning position) if pressure fluid be admitted to the cylinder at the end farthest from the front of the machine the piston and its stem and rack 43 will move toward the opposite end of the cylinder and revolve the toothed quadrant 48 to the left (looking at Fig. 2) causing the link to rock the feed frame 11, on pins 9 as a pivot to the right, thus carrying the upper master crankshaft to the right and rocking the tool feed frames to the right on the master crankshaft 14, as a pivot.

It is to be noticed in Fig. 2 that there are a pair of stops 54, in the side housings 2, and stops 55, in the feed frame to engage the stops 54. When these stops are in contact the tools 58, have reached a point where they are turning a true circle or may be said to be in the finishing position for the pins of a crankshaft.

In order to explain the operation of the device I have drawn lines 56 and 57—Figs. 1 and 2, which lines indicate the direction of coaxing eccentrics on the master shafts 14 and 15. It is to be noted in Fig. 1 that these lines are parallel so that the eccentrics are working together. It is only when these two centers of both the master crankshaft and their eccentrics are parallel that the tools then cut a true circle. Looking now at Fig. 2 wherein the feed frame 11 has been rocked on pins 9 to its most rearward position and the gears 17 thereby revolved which is the position when the tools 58 are farthest away from the work it will be noted that the line 56 is approximately at an angle of 18 degrees away from parallelism to the line 57 for the lower master shaft eccentric. In such a position the two eccentrics are not working together, because while they are alike to each other and move in complete synchronism, the upper one is in a different orbital

position from the lower. With the eccentrics so placed the movement of the tool will be an ellipse.

Each coating eccentric, of course, maintains the same relative angle, as the upper master shaft 5 is swung and hence slightly rocked due to the gearing connection.

When now the frame 11 is rocked forwardly as it is during the feeding stroke, the points of the tools describe an elliptical path, this elliptical 10 path gradually changing to a true circle as the angle of eccentricity of the upper eccentrics approaches the angle of the lower eccentrics, which is the position shown in Fig. 1.

This period of the feed of the tools, wherein the 15 tools are traveling in towards the pin in a gradually decreasing elliptical orbit is used to face the cheeks of the webs 60 of the crankshaft 59, shown mounted in the chucks 16 and the steady rests on the spacer frames 20.

20 As the tool approaches the pin of the shaft 59, the path of the tools becomes more circular and the cutting action on the cheek faces is more and more a turning action until when the close vicinity of the pin of the shaft is reached, the path 25 of the tool is, to all intents and purposes, a true circular path which becomes absolute as the pin is turned to its finished diameter.

While by providing for a differential gear drive to the two masters, a chain or idler gear 30 method of keeping the masters in parallel would accomplish a part of the objects of my invention, it is an advantage to have the working movement of the tool have an elliptical path and end up with a circular path. On other jobs of work 35 it might be of value to form an elliptical surface by reversing the arrangement described, since the masters can be so set as to synchronize with each other at any selected point of the planetary movement of the movable one.

40 Having thus described my invention, what I claim as new and desire to secure by Letters Patent, is:—

1. In a machine tool requiring an orbital tool 45 movement, a work holder, a series of tool holders, a masters having a series of throws of the orbital movement required, means for supporting the tool holders so as to move with the throws of said masters, and means for moving one first master to and from the work, thus accomplishing a feed for the tools on the holders, the last 50 named means comprising a frame in which movable master is supported and driving means for the movable master centered at the axis of movement of the frame, said tool holders being pivotally engaged with cranks on the movable master.

2. In an orbital lathe, the combination with a 55 frame of means thereon for engaging and rotating a crank shaft on its axis so that the crank pins move in an eccentric path, a series of tool carrier members spaced from each other, tools mounted on said carriers, means for moving said carriers eccentrically with the crank pins, and spacing means between the adjacent carriers, 60 said carriers and spacing means being held tightly together to prevent deviation of the tools incident to the necessary running fit of the carriers on the means for moving them.

70 3. In an orbital lathe, the combination with a frame of means thereon for engaging and rotating a crankshaft on its axis so that the crank pins move in an eccentric path, a series of carrier members spaced from each other, tools 75 mounted on said carriers, and spacing means

mounted on the frame and lying between the spaced carrier members and in bearing engagement therewith, and forming a solid metallic mass across the lathe.

4. In an orbital lathe, means for supporting and rotating a crank shaft of which the pins are to be operated upon, a movable frame, eccentric means rotating in the frame in synchronism with the crank shaft rotating means, tool carrying frames mounted on said eccentric means and moved thereby, said tool carrying frames being spaced apart from each other, and spacing means mounted in the lathe and lying between the spaced carrier members and in bearing engagement therewith and forming a solid metallic mass 80 across the lathe.

5. In an orbital lathe, a tool holder, a work holder, means for moving the tool holder in the orbital path required by the work, a fluid pressure motive device, a rack actuated by said motive device, a segment actuated by said rack, having an arm, and a pitman connecting said arm with said tool holder, said tool holder being pivoted for movement by said pitman to feed the tools to and from the work, while said tools follow the orbital path.

6. In an orbital lathe, a frame, a work holder and a master member rotatably mounted in said frame, a second master member, a feeding member supporting the second master member for 105 rotation therein and movably connected to said frame intermediate of the master members, a tool holder supported on the first master member and articulately connected to the second master member for movement by said master members orbitally to the work holder, and means for rotating the work holder and the master members in synchronism.

7. In an orbital lathe, a frame, a work holder and a master member rotatably mounted in said frame, a second master member, a feeding member supporting the second master member and pivoted to rock on said frame intermediate of the master members, a tool holder supported on the first master member and articulately connected to the second master member for movement by the master members orbitally to the work holder, and means for rotating the work holder and the master members in synchronism, comprising an intermediate transmission member 110 rotatable on the axis of rocking of said feeding member.

8. In an orbital lathe, a rotatable work holder and a rotatable master member operatively connected for synchronous rotation and relatively 115 rockable, a tool carried by the master member orbitally to the work holder and fed by the relative rocking, said relative rocking permitting the synchronous rotation for circular orbital movement of the tool concentric with the work holder at only one stage of the relative rocking, and means abutting together to positively stop the relative rocking at said stage.

9. In an orbital lathe, a rotatable work holder, a rotatable master member operatively connected 120 to said work holder for synchronous rotation therewith and rockable relatively thereto, a tool carried by the master member orbitally to the work holder and fed by the rocking of the master member, said rocking permitting the synchronous 125 rotation for circular orbital movement of the tool concentric with the work holder at only one stage of said rocking, and means abutting together to positively stop said rocking at said stage.
